UNITED STATES PATENT OFFICE.

CRAWFORD M. FAIRBANKS, OF PAWTUCKET, RHODE ISLAND.

TOOL-HANDLE.

SPECIFICATION forming part of Letters Patent No. 285,802, dated October 2, 1883.

Application filed April 27, 1883. (No model.)

To all whom it may concern:

Be it known that I, CRAWFORD M. FAIRBANKS, of Pawtucket, in the county of Providence and State of Rhode Island, have made 5 certain new and useful Improvements in Tool-Handles; and I do hereby declare that the following specification, taken in connection with the drawings making a part of the same, is a full, clear, and exact description thereof.

10 Figure 1 is a section of the handle, showing the interior devices for holding the tool. Fig. 2 is a view of the tool and holding devices, showing slight variation in construction. Fig. 3 is a section of the holder on line *x x*.
15 The object of my invention is to produce a tool-handle which shall be capable of adjustment to all tools having tangs of the ordinary form now in use; and it consists in the interior devices for that purpose, hereinafter described.

20 In the drawings, A, Figs. 1 and 2, is the tool, and B the handle. The handle B is made hollow, as shown, and has near its rear end a nut, C, which is introduced by means of a 25 transverse passage, D.

E is a holder having a screw tail-piece, F, and a head, G, slotted or made in two prongs, chambered upon the inside, to receive and hold a pair of eccentric rollers or balls, H, 30 which are secured therein upon axles passing through the head G.

The operation of my invention is as follows: The tang I of the tool is inserted in the head G of the holder, passing between the eccentric 35 rollers or balls H, whose construction and adjustment, as will be readily seen, permits such introduction, when the whole is inserted in the handle and the screw-thread upon the tail-piece F caused to engage the nut C. As the 40 tool and holder are now rotated they will be drawn down into the handle until the shoulders J J upon either side of the tang I come

in contact with the handle or ferrule upon the same. Another turn, or part of a turn, as may be necessary, will draw the shoulders and hold 45 them in solid contact with the handle and the tool securely in place. The tang I having been placed between the eccentric rollers, as described, cannot be withdrawn by a pull in the line of the tool, such a strain only serving to 50 increase the grip of the eccentric rollers upon the tang.

In Fig. 1 I show the rollers but slightly eccentric, and provided with springs K K, whose resistance tends to keep the rollers in contact 55 with the tang, while in Fig. 2 I have increased the eccentricity and rely on the weight of the rollers to impinge the tang in the first instance.

The faces of the rollers H may be milled or otherwise roughened, if it should be found necessary.

When it is desired to detach the tool, the tail-piece is unscrewed by rotating the tool and holder in the opposite direction until released from the nut; or the prongs may be 60 made to open after a slight elevation, and thus release the tang.

A tool-handle provided with the devices described is capable of receiving and holding tangs of the ordinary form, no alteration, 70 change, or special construction being required.

What I claim as my invention, and desire to secure by Letters Patent, is—

The combination of a handle provided with a holding means, as C, for the tool-holder, with 75 said tool-holder having eccentric rollers and the tool-tang inserted in the holder between said eccentric rollers and held thereby, substantially as set forth.

C. M. FAIRBANKS.
